WINDOW CONSTRUCTION

Willie Colangelo, Raton, N. Mex.

Application October 25, 1948, Serial No. 56,351

3 Claims. (Cl. 160—107)

1

The present invention relates to an improved window construction which embodies some of the features of my copending application, Serial No. 754,512, filed June 13, 1947, together with certain improvements thereover, which copending application has since been abandoned.

It is an object of the present invention to provide a window construction which includes a novel, wholly enclosed Venetian blind having remotely controlled means for raising and lowering the same as well as like means for angularly adjusting the slats thereof.

Another object of the invention is the provision of a device of the character set forth having means whereby easy access may be had to window panels forming a part of the invention.

Other and further objects of the invention will become apparent from a reading of the following specification, taken in conjunction with the drawings, in which:

Figure 1 is an exterior broken elevational view of an embodiment of the invention.

Figure 2 is an interior broken elevational view thereof.

Figure 3 is a sectional view taken along line 3—3 of Figure 4 rotated 90° clockwise.

Figure 4 is an enlarged broken sectional view taken along line 4—4 of Figure 2.

Figure 5 is an enlarged broken interior elevational view of the device shown in Figure 2 with certain parts removed.

Figure 6 is a sectional view taken along line 6—6 of Figure 4 rotated 90° clockwise.

Figure 7 is a sectional view taken along line 7—7 of Figure 4 rotated 90° clockwise.

Figure 8 is a fragmentary vertical sectional view taken along line 8—8 of Figure 5, and

Figure 9 is an enlarged fragmentary perspective view showing certain details of construction.

Generally, there is provided a window construction having an outer window pane and an inner window pane and having a Venetian blind mounted therebetween. The outer pane may be swingably mounted upon brackets for cleaning purposes and the inner pane may likewise be hingedly mounted to provide access to the interior mechanisms and also allow for cleaning. The Venetian blind is vertically movable by means of a revoluble handle mounted in the base of the device and the slats of the blind may be angularly controlled by a reciprocable cable which protrudes through the inner side of the base and which is equipped with an operating handle. Within the base there is provided an air passageway which is provided with louvers

2

at its outer side to prevent the entrance of snow and rain. Adjacent the louvers is mounted a filter screen to prevent the entrance of dust, insects and the like and centrally mounted in the passage is a damper which is controllable from the interior side of the base by a handle having means whereby the same may be latched in selected positions. The inner end of the passageway is also provided with a panel having louvers

10

therein.

Referring more particularly to the drawings, there is shown therein a window construction comprising a frame of wood or metal having a top member 10, side members 11 and 12 and a bottom member 13. The bottom member 13 may be slanted, as shown in Figure 4, to conform with the shape of the conventional window opening.

A base member 14 extends horizontally between the side members 11 and 12 and is spaced from the bottom member 13 to form an air passageway 15. At the outer end of the passageway 15 there is provided a series of uprights 16 which interconnect the base 14 and the bottom member 13 and a series of louvers 17 extend in spaced relation outwardly from the uprights.

Immediately inwardly of the uprights 16 there is provided a filter screen 18 which extends in a vertical plane and entirely covers the passageway 15.

Pivottally mounted upon the side members 11 and 12 of the frame by means of outwardly extending pins 19 carried thereby is a horizontally extending damper 20 which, when in a vertical plane, abuts at its upper end against a stop member 21 having a facing 22 of felt or the like and which is dependantly carried by the base 14. It also abuts at its lower end against a horizontally extending stop member 23 affixed to the upper side of the bottom 13 of the frame and which is likewise provided with a facing 24 of felt or the like.

The interior end of the passageway 15 is provided with a vertical panel 25 having openings or louvered openings 26 therein. There is also provided a centrally located opening 27 through which extends a damper handle 28 formed with teeth 29 upon its underside and a knob 30 or the like at its outer end and the inner end of the handle 28 is pivotally connected to an ear 31 mounted centrally upon the lower side of the damper 20. The sides of the damper 20 are faced with felt or the like, as indicated at 32.

An exterior window consisting of a pane 33 and sash 34 is mounted vertically between the top 55 10, sides 11 and 12 and base member 14 at the

outer side thereof and an interior window consisting of a pane 35 and sash 36 is likewise mounted at the inner side of the device.

Brackets 37 are dependantly affixed to the underside of the top 10 by screws 38 or the like adjacent either end of the top and each has mounted thereon a roller 39. In the lower end of each of the brackets 37 there is pivotally mounted a pin 40 which pins extend centrally from either end of the top guide slat 41 of a Venetian blind having conventional inner slats 42 and a bottom guide slat 43 interconnected in spaced relation by vertically extending tapes 44 at the front and rear thereof.

One end of the guide slat 41 has affixed thereto an angularly extending arm 45 to the outer end of which is affixed a cable 46 which extends through a flexible cable housing 47 downwardly through a metal cover 48 mounted upon the base 14 and thence through a passage 49 formed in the base and terminating in an operating button or handle 50 at the interior side of the base 14.

In a recess formed in the upper side of the base 14 there is provided a metal frame 51 in which is revolvably mounted a shaft 52 upon is affixed a pair of spools 53 and 54. Cords 55 and 56 are wound upon the spools 53 and 54, respectively, and extend over pulleys 57 and 58, respectively, mounted adjacent either end of the underside of the cover 48, and thence upwardly and over the pulleys 39 and thence downwardly through the bottom guide slat 43 and terminating in knots 59.

The shaft 52 extends through the interior wall of the base 14 and terminates in a handle 60.

In operation, it will be apparent that air may be admitted through the passageway 15 in any desired quantity by manipulating the handle 28 in such manner that a desired tooth 29 may engage with the lower edge of the opening 27 and thus changing the effective angle of the damper 20 to allow more or less air thereby. Also, when it is desired to close the passageway to the travel of air therethrough, the handle is pulled inwardly until it abuts the felt facings 22 and 24 of the stop members 21 and 23, respectively. The louvers 17 prevent rain or snow from entering the passageway and the filter screen 18 will keep out dust and insects, while the perforated panel 25 will allow for an even flow of air into the interior of the building in which the device is utilized.

To tilt the Venetian blind in conventional manner, it is only necessary to move the cable 46 in or out by means of the button 50 thereby moving the arm 45 and hence the guide slat 41 which will, in turn, move all other slats through the interconnecting webs or tapes 44.

To raise or lower the Venetian blind, it is only necessary to revolve the handle 60 thereby moving the cords 55 and 56 onto or off of the spools 53 and 54 thus moving the bottom guide slat 43 upwardly or downwardly depending on the direction of rotation of the handle 60.

A spring 61 interconnects the ear 31 and an eye 62 adjacent the inner edge of the bottom member 13 to normally urge the damper 20 to closed position. The felt facings 32 on the sides of the damper provide a means for frictionally holding the damper in selected positions and also acts as insulation.

While but two forms of the invention have been shown and described herein, it will be readily ap-

parent to those skilled in the art that many minor modifications may be made without departing from the spirit of the invention or the scope of the appended claims.

5 What is claimed is:

1. A device of the character described comprising a frame, inner and outer windows in the frame, a Venetian blind suspended from the top of the frame between said windows, remotely controlled means for adjusting the angular relation of the slats of the blind and remotely controlled means for raising and lowering the blind, said last named means comprising a shaft transversely mounted in the base of said frame, a pair of spools affixed to the shaft, cords interconnecting each of these spools and the lowermost slat in the blind, pulleys for guiding the cords and a handle at the intermost end of the shaft.

10 2. A device of the character described comprising a frame, inner and outer windows in the frame, a Venetian blind suspended from the top of the frame between said windows, remotely controlled means for adjusting the angular relation of the slats of the blind and remotely controlled means for raising and lowering the blind, said last named means comprising a shaft transversely mounted in the base of said frame, a pair of spools affixed to the shaft, cords interconnecting each of these spools and the lowermost slat in the blind, pulleys for guiding the cords and a handle at the intermost end of the shaft, said means for remotely controlling the angular adjustment of the slats of the blind comprising an arm carried by one of the slats, a cable connected at one end with the arm and extending through the frame and having an operating button at its outer end.

15 3. A device of the character described comprising a frame, inner and outer windows in the frame, a Venetian blind suspended from the top of the frame between said windows, remotely controlled means for adjusting the angular relation of the slats of the blind and remotely controlled means for raising and lowering the blind, said last named means comprising a shaft transversely mounted in the base of said frame, a pair of spools affixed to the shaft, cords interconnecting each of these spools and the lowermost slat in the blind, pulleys for guiding the cords and a handle at the intermost end of the shaft, said means for raising and lowering the blind comprising a shaft transversely mounted in the frame, pulleys for guiding the cords, said handle being operative for turning the spools and actuating the cords.
